Primary Examiner — Jeffrey D Asch*Assistant Examiner* — Rebekah A Caruso(74) *Attorney, Agent, or Firm* — Muncy, Geissler, Olds & Lowe, P.C.(57) **CLAIM**

The ornamental design for an antenna, as shown and described.

DESCRIPTION

FIG. 1 is a front view of an antenna showing my new design; FIG. 2 is a rear view thereof;

FIG. 3 is a right side view thereof;

FIG. 4 is a left side view thereof;

FIG. 5 is a front, right perspective view thereof;

FIG. 6 is a front, top perspective view thereof; and,

FIG. 7 is a front, left perspective view thereof.

The dark shaded feature that encircles the antenna's opening is a continuous width groove centered within the elliptical opening.

1 Claim, 7 Drawing Sheets(56)
